CLAIM

The ornamental design for scissors handle, as shown and described.

DESCRIPTION

FIG. 1 is a perspective view of a scissors handle showing my new design, the broken line drawing of the scissors is for illustrative purposes only and forms no part of the claimed design;

FIG. 2 is a front elevational view thereof, the broken line drawing of the scissors is for illustrative purposes only and forms no part of the claimed design,

FIG. 3 is a rear elevational view thereof, the broken line drawing of the scissors is for illustrative purposes only and forms no part of the claimed design;

FIG. 4 is a left elevational view thereof, the broken line drawing of the scissors is for illustrative purposes only and forms no part of the claimed design;

FIG. 5 is a right elevational view thereof, the broken line drawing of the scissors is for illustrative purposes only and forms no part of the claimed design;

FIG. 6 is a top plan view thereof, the broken line drawing of the scissors is for illustrative purposes only and forms no part of the claimed design; and,

FIG. 7 is bottom plan view thereof, the broken line drawing of the scissors is for illustrative purposes only and forms no part of the claimed design.
